UNITED STATES PATENT OFFICE.

WILLIAM L. JENKINS, SR., AND WILLIAM L. JENKINS, JR., OF NILES, OHIO.

DOUBLER.

1,313,635.

Specification of Letters Patent.

Patented Aug. 19, 1919.

Application filed March 7, 1919. Serial No. 281,118.

To all whom it may concern:

Be it known that we, WILLIAM L. JENKINS, Sr., and WILLIAM L. JENKINS, Jr., citizens of the United States, both residing 5 at Niles, in the county of Trumbull and State of Ohio, have invented new and useful Improvements in Doublers, of which the following is a specification.

Our invention relates to machines for doubling or folding sheets and plates. It was especially designed for doubling metal sheets in a sheet mill, but it may be used for various other purposes. The top of the machine is preferably on the level of the mill 15 floor adjacent to one or more stands of rolls.

It is common practice for the workmen to double or fold the sheets in a sheet mill by the aid of tongs which are used to bring the opposite edges of the sheets together, 20 while the middle portions are beaten down by workmen jumping on them or by the use of tongs or other devices. It is the object of the present invention to do the doubling entirely by machinery after the sheets are 25 laid upon the machine. It is a further object to provide gages whereby the sheets may be automatically adjusted transversely so as to be bent truly at right angles with their sides. We provide adjustable gages for centering or adjusting the sheets longitudinally 30 so that they may be doubled on any selected transverse line. We provide also novel mandrel or hold-down devices for the metal at the place where it is to be bent. Preferably 35 we use one of these devices as one of the gages for adjusting the sheets at right angles to the line of folding. Other objects will appear hereinafter.

Referring to the accompanying drawings, 40 Figure 1 is a plan view of one form of our novel machine, with parts broken away; Fig. 2, a vertical section on the line II—II of Fig. 1; Fig. 3, a side elevation of Fig. 1, with the doubler leaf or member partly 45 elevated; Fig. 4, an end elevation of our said machine; and Fig. 5, a skeleton plan of some of the gage mechanisms.

On the drawings, 1 designates the horizontal base or bed of our machine, and 3, 50 4, and 5 are three vertical parallel members erected on the base 1. 6 is a drive-pulley on the shaft 7 journaled in the member 4 and the standard or support 8. The shaft 7 has the pinion 9 which meshes with the spur-gear 10 on the crank-shaft 11 journaled in

the members 3 and 4. To the crank 12 on the shaft 11 is connected one end of the pitman 13, having its remaining end pivoted to one end of the reciprocating rack 14 guided between the ways 15 resting on the base between the members 3 and 4. The rack gears with the pinion 16 on the shaft 17 journaled in the members 2 and 3. The clutch 7 connects the pulley 6 with the shaft 7. 60 18 is the sheet folding member secured rigidly to the shaft 17 so as to travel therewith. This member is in general a flat metal plate adapted to lie in one position flush with the top of the machine or slightly below the said top when the shaft is rotated to its 65 extreme position in one direction, and to lie up on the left hand end 19 of the machine when the shaft is rotated to its extreme position in the opposite direction. In Figs. 1 and 2, which show our machine with its 70 parts ready for a folding operation, it will be noticed that the member 18 has a downward bend 20 near the shaft 17 to receive the metal adjacent to the folded line at the close of a folding operation in case it should buckle or hump at the line of folding. The outer or free end of the folding-member 18 is preferably cut away at each side as shown at 21, and rests upon the slotted right-hand end 22 of the top of the machine, this end of the top 75 lying a little below the members 2 and 3. The member 18 has the slot 23 extending from the free end thereof toward the shaft 17 and lying midway between the sides of the member. 80

Beneath the slot 23 is a pair of spaced horizontal guides 24 supported by the legs 25 on the base 1. On these guides the gage-holder 26 is slideable beneath the slot and in line therewith. The gage-holder has a number of holes arranged lengthwise thereof, any one being adapted to receive the vertical gage-pin 27 extending up through the slot 23 above the table-top. To the bottom of the table-top 19 at the opposite end of the 85 machine from the guides 24, we secure the spaced guides 28, on which the gage-holder 29 reciprocates toward and from the shaft 17 midway between the members 2 and 3. This gage-holder has several holes arranged 90 lengthwise thereof to receive the gage-pin 30, which travels in the slot 31 in the top 19. 100

32 is a rock-shaft journaled in the supports 33 on the base 1 and is operated by the handle 34. The rock-shaft is secured to 105 110

the center of the bar 35 which has its upper end connected to the gage-holder 29 by the pitman 36 and its lower end connected to the pitman 37. The latter is connected to the bar 38 for operating the gage-holder 26. As the handle 34 is moved the gage-holders 26 and 29 move simultaneously toward and from each other equal distances.

We provide in recesses in the member 3
10 two gage fingers 39 and 40 extending slightly above the table, at opposite sides of the line on which the sheets are to be folded. These gage-fingers are guided in their movements transversely of the machine by the rods 41 and 42 secured in pairs in the members 2 and 3. 43 is a rock-shaft journaled in the blocks 44 and 45 on the rods 41 and 42, and in the block 46 on the rods 47 secured in the members 2 and 3 between the rods 41 and 42.
15 The shaft 43 is provided with the arms 48 and 49. The arm 48 extends equally above and below the shaft 43 and has its lower end connected to the block 39 by the link 50. The arm 49 extends below the shaft 43
20 and is connected to the block 40 by the link 51. The rods 47 carry the sliding finger 52, which is slightly back of a line joining the inner faces of the gage-fingers 39 and 40, and is moved on those rods by the link 53
25 connected to the lower end of the arm 48. The rods 47 carry also the sliding gage-finger 54 set in a recess in the member 2. This finger is connected by the link 55 to the upper end of the arm 48. The fingers 52
30 and 54 each has a horizontal mandrel or hold-down pin 56 extending, one toward the other, slightly above the top of the table and a little to the left of the shaft 17.

The shaft 43 is provided with a horizontal
40 arm 57, connected by the vertical link 58 to the arm 59 on the rock-shaft 60, which is operated by the handle 61.

The parts being as in Figs. 1 and 2, a sheet to be doubled is placed on the doubler-member 18 and on the end 19 of the table with its ends between the gage-pins 27 and 30, and its sides between the gage-fingers 39 and 40 and the finger 54. The handle 34 is operated which causes the sheet to be centered so as to bring the place to be folded exactly in line
45 with the mandrel pins 56. The handle 61 is then operated to cause the fingers 39 and 40 and the finger 54 to center the sheet, the sheet engaging both the fingers 39 and 40 and thereby insuring that the sheet will lie exactly at right angles to the fold to be made
50 over the pins 56. The operation of the handle 61 causes the pins 56 to pass above the sheet or pack to be bent. The belt wheel 6
55 being set in operation by a motor or by the clutch connection 7, or other power transmitting means, the rack 14 is caused to move to the left, which causes the doubler-member 18 to turn with the shaft 17 and double or
60 bend the right-hand end of the sheet over
65

the pins 56 until it lies upon the left-hand end thereof. The continued movement of the wheel 10 causes the rack to move to the left and the doubler member to return to its original position, when the machine is stopped preparatory to another operation.

We claim:

1. In a doubler, a table, a gage-holder at each end of the table movable toward and away from the center thereof and having 75 holes arranged lengthwise of the table, a gage-pin for each holder, each gage-pin being insertible in any hole in its respective holder, means for moving the gage-holders simultaneously toward and from each other, 80 and means for doubling a sheet adjusted between the gage-pins.

2. In a doubler, a table, two gage-fingers thereon for one side of a sheet, the fingers being on opposite sides of the line where 85 the sheet is to be doubled, a single movable gage-finger engageable with the remaining side of the sheet to cause the sides of the sheet to engage all three gage-fingers, mandrel pins over which the sheet may be bent, 90 one of the pins being carried by the single finger, and means for doubling the sheet transversely between the first two gage-fingers and over the mandrel pins.

3. In a doubler, a table, two gage-fingers 95 thereon for one side of a sheet, the fingers being on opposite sides of the line where the sheet is to be doubled, a movable gage-finger engageable with the remaining side of the sheet to cause the sides of the sheet 100 to engage all three gage-fingers, a mandrel pin carried by the movable gage finger and movable over the edge of the sheet, a second mandrel pin movable over the other edge of the sheet, and means for doubling the 105 sheet transversely between the first two gage-fingers and over the mandrel pins.

4. In a doubler, a table, a doubler member thereon, and a rock-shaft carrying the same, there being a transverse bend in the said member adjacent to its axis of movement and adapted to lie somewhat above the line at which the sheet is doubled to receive any surplus metal protruding above the line of doubling.

5. In a doubler for sheets, gage-fingers adapted to engage the opposite sides of sheets of different widths and to adjust them, and a mandrel over which the sheets may be doubled, the mandrel being carried by and movable with one of the gage fingers.

6. In a doubler, a pair of opposing mandrels over which a sheet thereon may be doubled, a carrier for each mandrel, a table for the sheet having lateral recesses into 125 which the mandrels and their carriers may rest out of the lines of travel of the sides of the sheet as it is fed upon the table, means for projecting the mandrels over the edges of the sheet, and a pair of gage fingers on 130

opposite sides of the sheet, one of the gage-fingers being movable with one of the carriers transversely of the sheets so as to engage the edge of sheets of different widths
5 while in engagement with the other gage-finger.

Signed by the said WILLIAM L. JENKINS,

Sr., at Canonsburg, Pa., this 4th day of March, A. D. 1919, and by the said WILLIAM L. JENKINS, Jr., at Canonsburg, Pa., this 10 4th day of March, A. D. 1919.
